FIG. 4 is a bottom plan view thereof; and,

FIG. 5 is a top plan view thereof.

1 Claim, 5 Drawing Sheets

FIG. 1

FIG. 2

FIG. 3

FIG. 4

FIG. 5

UNITED STATES PATENT AND TRADEMARK OFFICE
Certificate

Patent No. D. 420,094

Patented: February 1, 2000

On petition requesting issuance of a certificate for correction of inventorship pursuant to 35 U.S.C. 256, it has been found that the above identified patent, through error and without deceptive intent, improperly sets forth the inventorship.

Accordingly, it is hereby certified that the correct inventorship of this patent is: James A. Woodard, Jr., Columbus, OH; Keith H. Gausmann, Delaware, OH; Dale Aberegg, Mount Vernon, OH; Roy M. Taylor, Jr., Rockford, MI; and Dennis J. Kool, Kentwood, MI.

Signed and Sealed this Sixth Day of November 2001.
